DRESS SHOULDER PAD

Lewis I. Serbin, Shaker Heights, Ohio, assignor
to Serbin Sportswear Co., Cleveland, Ohio, a
general partnership

Application January 4, 1946, Serial No. 639,023

1 Claim. (Cl. 2—268)

1

The invention relates to garment pads and to novel means for removably retaining such pads at suitable locations in garments. While the invention is obviously adapted to general use, it will be described with particular reference to shoulder pads in women's clothing.

An object of the invention is to provide novel pad-retaining means which is more or less permanently attached to the garment, but which permits ready insertion or removal of the pad.

Another object of the invention is to provide pad-retaining means as above specified, which prevents accidental dislodgment of the pad while the garment is in use.

A further object of the invention is to provide a pad, and pad-retaining means, said means being of novel structure, and having a contour particularly adapted to use in connection with a generally triangular shoulder pad.

Other objects and advantages will be apparent from a study of the following specification in conjunction with the accompanying drawings, in which:

Fig. 1 is a bottom plan view of the pad-retaining means, hereinafter termed, for convenience, a cover;

Fig. 2 is a sectional view taken on the line 2—2 of Fig. 1, and showing a pad in position within the cover;

Fig. 3 is a fragmentary perspective view showing a cover in position in a garment, the cover being shown in broken lines;

Fig. 4 is a sectional view taken approximately on the line 4—4 of Fig. 3;

Fig. 5 is a plan view, somewhat reduced in size, and taken similarly to Fig. 1, but showing a slightly modified embodiment of the invention.

Those skilled in the garment art are familiar with the fact that garment pads should be removable to facilitate laundering and cleaning operations, since the pads normally absorb considerable moisture, and are subsequently dried only with difficulty, thereby greatly prolonging the drying time of the garment as a whole. Presence of the pad also interferes with proper pressing or ironing operations. Various means and methods have been devised for permitting removal of the pad, but such methods and means have usually involved tacking the pad in place by stitching which must be cut away to extricate the pad, or loosely retaining the pad in some sort of sheath or cover which often permits the pad to fall out while in use.

The means now to be described permits ready

removal of the pad, but holds it securely in place while the garment is in use.

Referring now to Figs. 1 to 3, wherein I show pad-retaining means adapted to hold a shoulder pad for a wash dress, the pad 10 is of general triangular contour in plan view, and is disposed within the cover 11, also triangular in shape. The face 12 of the cover, which is normally next to the garment, is continuous, but the exposed face is divided by a slot 13, extending transversely of the face, and defined between two front wall portions 14 and 15. The two faces are connected along their edges to enclose a pad receiving pocket to which access is had through said slot. 15 A terminal lip portion 14a of wall 14 overlaps a complementary terminal lip portion 15a of wall 15.

Cover 11 is securely attached to the shoulder portion 16 of the dress (Fig. 3) with the unslotted face 12 adjacent the dress, and with the slot 13 turned downwardly so as to be readily accessible. By reason of the flexibility of the cover material, the triangular pad 10 can be pushed inwardly through the slot so that its three corners nest within the respectively complementary corners of the cover. Since the slot 13 is substantially parallel to a base edge 17 of the triangular cover, at a position intermediate said base edge and an opposed apex, the corner 18 of the pad remote from said base is securely trapped, and will not fall out accidentally but must be extricated manually. The base edge 19 of the pad, which is substantially parallel to the slot 13, is wider in lateral extent than the slot 13 between the side stitchings 20, and this feature prevents accidental dislodgment of the pad. The cover is stitched along the dotted line 20. In the embodiment shown such stitching runs through the end edges of the lapped portions 14a and 15a.

Fig. 5 illustrates a slightly modified embodiment of the invention in which the cover is of segmental contour defined by two angularly spaced sides 22, 23, and a curved base 24. The structure is similar, in most of its details, to the embodiment shown in Fig. 1, except that the base 24 is curved, rather than straight, so as to conform to a curved line where the dress sleeve meets the shoulder. In this instance the contour of the enclosed pad 25 is similar in shape to the cover and has a curved side parallel to the base 24.

The slot 26 is similar in position and function to slot 13 already described in connection with Figs. 1 to 4.

The cover is usually sewed to the inside face of the shoulder of the dress by tacking stitches at several points around the periphery of the cover. Thus the cover remains in place when the dress is washed and ironed and causes no difficulty. The pad is removed during such washing and ironing operations by bending or folding it sufficiently to slip it out through slot 13.

What I claim is:

Pad-retaining means consisting of a pad cover generally triangular in plan view, and having two generally parallel faces permanently united along the three edges thereof to define a pad receiving pocket, one said face being of continuous character, and the other face being provided with an open slot extending transversely across it from an intermediate point of one edge to an intermediate point of another edge, said slot being adapted to permit a dress pad to be inserted therethrough into said pocket, one lip of said slot overlapping the other lip of said slot throughout its length, said slot being substantially parallel to the third edge of said cover, a generally triangular pad inside said cover having a base generally parallel to said third edge

10

of said cover, said pad base being longer than said slot whereby the base corners of said triangular pad extend laterally beyond the ends of said slot into the corners of said cover at opposite ends of said third edge so that said pad is thereby retained in said cover, and tacking stitches securing said cover to a garment with said face of continuous character against the garment.
